COIN SELECTOR

John Gottfried, St. Louis, Mo., assignor to National Slug Rejectors, Inc., St. Louis, Mo., a corporation of Missouri

Application June 11, 1941, Serial No. 397,594

1 Claim. (Cl. 194—101)

This invention relates in general to coin selectors, and more particularly to improvements in coin selectors for accepting coins of two denominations and separating spurious coins or tokens therefrom.

This device utilizes the general principle whereby coins propelled by gravity are passed through an intense magnetic field to change their normal trajectories in proportion to their relative conductivities and thence the coins traveling in free trajectories are subjected to an impact test to measure their relative resiliency to separate acceptable coins from spurious coins, tokens, etc.

In previous selectors of this character where coins of two different denominations were utilized it was necessary to employ separate magnetic fields in their respective coin passages for the coins of each denomination.

In the present invention two coin paths for conducting coins of different denominations are subjected to the same magnetic flux through the use of selected materials and the novel placement of a pair of permanent magnets.

The principal object of the invention is the provision of an intense magnetic field at right angles to and through two parallel coin passageways.

A further object of the invention is the provision of paramagnetic pole pieces between two adjacent coin passageways for providing concentrated flux paths through the two passageways.

With these and other objects in view, my invention lies in the novel combination and arrangement of elements described, two embodiments of which is shown in the accompanying drawing, in which:

Fig. 1 is a side elevation of the device with cover member removed.

Fig. 2 is an elevation of the side opposite Fig. 1, with cover member removed.

Fig. 3 is a sectional end elevation taken through section line 3—3, Fig. 1.

Fig. 4 is a fragmentary elevation of an alternative construction taken through section line 3—3, Fig. 1, showing the application of auxiliary pole pieces.

Fig. 5 is a fragmentary view of the device showing the auxiliary pole pieces shown in Fig. 4.

Referring to Fig. 1, main plate 1 serves as a frame for the entire apparatus. This plate may be made of paramagnetic material, and as an alternate, may be constructed of diamagnetic material, such as brass, in conjunction with auxiliary pole pieces, to be hereinafter described.

Gate 2 is secured to the side of the plate by pivots 3 and 4 and is held in close proximity with the surface of the plate 1 by spring 5 positioned about pivot screw 3 and engaging the gate at stud 6 at one end and having its opposite end in contact with the surface of the plate 1. The space between the gate and the plate 1 serves as an entrance passageway for coins in the upper left-hand portion of Fig. 1. A sloping land 7, integral with the gate, protrudes inwardly and contacts the frame to provide a coin runway over which the coins are directed. A diamagnetic offset bracket 8 is secured to the inside surface of the plate 1 by screw 9 and serves to retain a two-pole permanent magnet assembly 10 with its pole pieces flush with the inside surface of the bracket, thereby providing a continuation of the coin passageway between the bracket and the flush surfaces of the magnet pole pieces and the plate 1.

The magnet assemblies 10 and 21 consist of a simple horse shoe magnet cast into a housing of diamagnetic material such as zinc alloy or plastic composition. This construction provides a simple means for securing the magnet in proper relationship with the other elements of the device.

When a proper coin is deposited in the runway in the upper left-hand opening between the gate 2 and the main plate 1, it will descend by gravity to the land 7 and continue its movement downward along the land 7 between the bracket 8 and the main frame 1 to pass the pole pieces of the magnet assembly 10 and thence in a free trajectory to a point 11 on the anvil 12, where the coin will rebound over barrier 13 to the acceptance passageway 14.

The side of the device shown in Fig. 1 is adapted for the use of nickel alloy coins such as the U. S. 5¢ piece.

Referring to Fig. 2, which shows the opposite side of the device, a gate 2—a is pivotally mounted upon the main plate 1 by pivots 15 and 16 and positioned symmetrically opposite the gate 2 on the opposite side of the plate. The gate is held in close proximity with the main plate by spring 17, one end of which is secured to the stud 18 integral with the gate and its opposite end urged against the inside surface of the plate 1. A sloping land 19, integral with the gate 2—a, is adapted to provide a runway for coins deposited under the influence of gravity in the opening at the upper right-hand portion of the gate.

A diamagnetic offset bracket 20 is retained by screw 9 to the main plate 1 and serves as a support for a magnet assembly 21 having two pole pieces flush with its inside surface, thus providing

a passageway for the moving of coins between the inside surface of the bracket 20 and the plate 1. The magnet assembly 21 is positioned so that its pole pieces are directly opposite the pole pieces of magnet assembly 10 secured to the opposite side of the plate.

Since this side of the selector is adapted for the separation of high conductivity coins, such as the U. S. silver 10¢ piece, the anvil 12 is omitted and two adjustable abutments substituted to carry the coins in proper paths.

Abutment 22 is positioned in a manner whereby coins having conductivity higher than that of acceptable value will impinge thereupon and be deflected into a rejection passageway 23. An abutment 24 is pivotally mounted upon a support 25 at 26 and adapted to assume the position shown in solid lines, Fig. 2, through the action of gravity. The offset end of abutment 24 is adapted to engage the edge of a coin moving in a free trajectory. Abutment 24 is adapted to be tilted by the impact of a coin to the position shown in dotted lines.

Coins of acceptable conductivity, after leaving the land 19 in a free trajectory, will impinge upon the abutment 24 and thus move it downwardly against the restraining action of gravity sufficiently far to cause a dime to roll to the right of the offset portion into the acceptance passageway 14.

It has been found that coins having borderline acceptance values are accurately separated by means of the pivotally mounted abutment by taking advantage of their slightly different weights and trajectories through the compensating action of the tilting abutment.

Referring to Fig. 3, the passageway adjacent to the magnet assembly 10 for the nickel coins is clearly shown at 27 and the passageway for coins of high conductivity is shown at 28 between the magnet assembly 21 and the main plate 1, both passages being parallel upon opposite sides of the main plate 1 and between the magnet assemblies 10 and 21.

When plate 1 is made from paramagnetic material it is obvious that the portions of the plate between the pole pieces of the two magnet assemblies will serve as conducting media for the magnetic flux which traverses both the coin passageways 27 and 28.

In the alternate method of construction, and referring to the fragmentary figures 4 and 5, when a diamagnetic plate is utilized, two paramagnetic inserts 29 and 30 are shown retained in apertures in the main plate 1 for providing high permeability paths for the flux of the magnet assemblies 10 and 21. The pole pieces, as shown in Figs. 4 and 5, are positioned between the magnet assemblies and opposite their respective poles, thus two paths of intense confined magnetic field are projected substantially at right angles to the passageways 27 and 28, which paths are traversed by coins passing in either runway.

It has been found that, due to the concentrating effect of auxiliary pole pieces 29 and 30, sufficient magnetic flux to properly test the conductivity of coins is attainable with permanent magnets of lesser size than those required when the auxiliary pole pieces are omitted and a para-

magnetic plate is positioned between the magnet assemblies.

In operation, and assuming that a nickel alloy coin is deposited in the entrance passageway, shown in Fig. 1 it will roll along the land 7 and intercept the magnetic flux provided by the two magnet assemblies 10 and 21 and then continue in a free predetermined trajectory determined by the strength of the magnetic flux to a point 11 upon the anvil 12 and thence rebound over barrier 13 into the acceptance passageway 14.

Spurious coins and other coins having different conductivity and resilience will define a different path after passing through the magnetic field and thence will be conducted to the rejection passageway 23.

Assuming a proper coin of high conductivity, such as silver, is deposited in the right-hand entrance, shown in Fig. 2, it will likewise roll along the sloping land 19 and traverse the intense magnetic field and fall in a free trajectory and be intercepted by abutment 24 where it will rebound to the right into the acceptance passageway 14.

In the event a coin of greater conductivity than an acceptable coin is deposited in the runway shown in Fig. 2, it will traverse the magnetic field and its trajectory will be shorter, thus the coin will impinge upon abutment 22 and be deflected into the rejection passageway 23.

In the event a coin having lesser conductivity than that of an acceptable value is deposited in the runway shown in Fig. 2, the trajectory will be greater and hence the coin will impinge upon abutment 24 sufficiently far to the left to be deflected into the rejection passageway 23.

Through the action of means not shown, the gates 2 and 2-a may be opened to release articles suspended in the passageway and also, through additional apparatus not shown, the magnet assemblies can be manually cleared of paramagnetic coins which may have been retained against the magnet pole pieces.

Having described my invention, I claim:

In a coin selector for receiving coins of two denominations propelled by gravity, a sloping coin runway for conducting coins of one denomination, a second coin runway positioned adjacent to and running parallel with the first-named coin runway for conducting coins of second denomination, a pair of bi-pole permanent magnets positioned in and adjacent with opposite outside walls of said runways, the pole faces of said magnets positioned opposite each other with a space therebetween, a diamagnetic partition positioned between the runways and the said magnets, a pair of paramagnetic pole pieces positioned in said diamagnetic partition adjacent to and in spaced relation with the poles of said magnets, said pole pieces having areas substantially the same size as the areas of said magnet pole faces, said magnets adapted to provide a magnetic field traversing both the said runways and concentrated through the said pole pieces, whereby coins of two denominations moving in their respective runways will be intercepted by the said magnetic field to change the respective velocity of each said coin in proportion to its conductivity.

JOHN GOTTFRIED.
